United States Patent Office

Des. 224,287

Patented July 18, 1972

224,287

BOTTLE OR SIMILAR ARTICLE

Theo M. S. Coster, Beyt Horon St. 7,
Tel Baruch, Israel

Filed July 10, 1970, Ser. No. 23,893

Term of patent 14 years

Int. Cl. D9—01

U.S. Cl. D9—157

FIG. 1.

FIG. 2.

FIG. 4.

FIG. 3.

FIG. 5.

FIG. 1 is a perspective view of a bottle or similar article showing my new design;

FIG. 2 is an elevational view;

FIG. 3 is a sectional view taken on the line 3—3 of FIG. 2;

FIG. 4 is an elevational view looking in the direction of the arrows 4—4 of FIG. 1; and

FIG. 5 is a plan view looking in the direction of the arrows 5—5 of FIG. 4.

I claim:

The ornamental design for a bottle or similar article, as shown.
